UNITED STATES PATENT OFFICE.

HARVEY C. LOWRIE, OF DENVER, COLORADO.

MEANS FOR SECURING CIRCULAR DOORS OR COVERS TO CASINGS.

SPECIFICATION forming part of Letters Patent No. 739,328, dated September 22, 1903.

Application filed December 2, 1902. Serial No. 133,571. (No model.)

To all whom it may concern:

Be it known that I, HARVEY C. LOWRIE, a citizen of the United States, residing at Denver, in the county of Arapahoe and State of Colorado, have invented new and useful Improvements in Means for Securing Circular Doors or Covers to Their Casings, of which the following is a specification.

My invention relates to means for locking a circular door or cover to its casing in such a manner as to require for its removal a series of rotary movements such as is necessary for opening an ordinary combination-lock.

My invention has been devised more especially for securing the door or cover of a safe or lock-box; and it consists in certain improvements upon the locking mechanism disclosed in United States Letters Patent No. 693,142, granted to me February 11, 1902. In the aforesaid Letters Patent I show a safe-door which is locked to its casing by circular tumblers or rings mounted in said casing and adapted to be moved by rotary movements of the door into and out of alinement with each other, so as to be placed in or out of engagement with lugs or projections on the door with which said rings coöperate for locking it to the said casing. In said patent the locking-rings or tumblers are mounted in a thread-

30 ed bushing which is screwed in the door-casing, said bushing being constructed in two semicircular sections to permit the rings to be assembled therein. The rings are held together by said bushing only when the latter is in place in the door-casing. This construction aside from the expense involved in manufacturing and assembling the parts necessitates a determination of the unlocking combination of each safe after all of the parts 35 have been properly assembled and prevents a ready removal and replacement of the locking mechanism, should such for any reason be necessary or desirable.

The main object of my present invention is 40 to so construct the locking mechanism that its several parts may be secured together to form a unitary structure that can be readily applied to or removed from the safe without the use of tools and without liability of disturbing the opening combination to which the lock may be adjusted. This enables the locks 45 to be made in large quantities and the open-

ing combination of each to be determined apart from the safes to which they are to be applied, and I am also enabled to employ duplicate parts in the construction of each lock, which greatly reduces the cost of its manufacture. 55

After a detail description of my invention the features deemed novel will be specified in the claims hereunto annexed.

Referring to the drawings furnished and forming a part of this specification, Figure 1 is a front view of a safe-door and door-casing embodying my invention. Fig. 2 is a side elevation of the door with its casing and locking mechanism shown in section. Fig. 3 is a front view of the casing with the door removed. Fig. 4 is a rear view of the door; and Figs. 5, 6, and 7 are front, rear, and sectional views, respectively, of the locking mechanism detached from the door-casing. 60

As hereinbefore indicated, my invention is designed more especially for safes or lock-boxes provided for the storage of money or articles of value; but it will be obvious that a device or mechanism embodying my invention may be employed wherever it may be desirable to secure a cover to a circular opening in such manner as to prevent its unauthorized removal. 70

The door 1 (illustrated in Figs. 1, 2, and 4) is circular in outline and fits in a similarly-shaped casing 2, formed in the wall 3 of a safe, lock-box, or other receptacle. Said door 80 is to be rotated in its casing for adjusting the locking mechanism and is therefore provided with a handle or knob 4, and around the outer edge it is provided with numbered graduations 5, which, in connection with an index 6 on the door-casing, enables any one knowing the proper combination to so rotate the door as to properly adjust the tumblers or locking-rings, to be hereinafter described. Around the periphery of the door are three 85 lateral projections or lugs 7, 8, and 9, and around the interior of the door-casing are three lugs or projections 10, 11, and 12, which correspond in length and relative location to the spaces between the lugs 7, 8, and 9 on the 90 periphery of the door, and they are so arranged that by turning or revolving the door after it is inserted in its casing they will engage the lugs on the door and prevent it from 95 100

being withdrawn. These several lugs are so located and proportioned as to length as to hold the door in every position of adjustment to which it may be turned except at the one 5 particular adjustment at which the lugs on the door will be opposite the spaces between the lugs in the door-casing. The rear of the door is provided with lateral projections or lugs, which are engaged by tumblers or locking-rings 13 and 14. There may be any number of these tumblers or rings, but each ring will require separate adjustment in unlocking the door, and the greater the number of locking-rings employed the greater will be 10 the time required for adjusting them to their unlocking position. The rear of the door is provided with lateral projections or lugs 15, 16, and 17, preferably three in number for each locking-ring. These lugs pass through 15 the rings when the door is inserted in its casing and engage with the locking-rings for preventing a withdrawal of the door after the latter has been turned from its initial position. The opening through the rings should 20 correspond in shape to the contour of the door around the lugs 15, 16, and 17, which must pass therethrough. Much time and study has been given by me to so shaping the opening through the rings and so forming the 25 lugs on the door that the latter will be held by the rings in every position to which the door may be adjusted except at the one point at which the door may be inserted and withdrawn. The opening through the rings has 30 therefore been formed as illustrated in Fig. 5. In said figure a circle has been drawn in dotted lines, which touches the inner edges of the ring at the narrowest portion of the opening, and a second circle, concentric with 35 the first, is drawn to just touch the widest portions of said opening. The space between the two circles indicates the path of the lugs 15, 16, and 17 on the door when the latter is rotated in its casing. Said lugs 15, 16, and 40 45 17 are shaped to correspond to the open spaces between the dotted circles in Fig. 5, and all of those portions of the locking-ring embraced between said circles coöperate with said lugs for locking the door. The contour of the 50 rear portion of the door around the locking-lugs 15, 16, and 17 exactly corresponds to the opening through the locking-rings, the latter, however, being of sufficient size to permit the former to pass freely therethrough. 55 The locking-rings 13 and 14 are mounted in a cylindrical frame or housing 18, which is provided with interior annular grooves 19 and 20, in which said rings are seated. The ring-housing is built up of counterpart rings 50 55 60 65 70 75 80 85 90 95 100 105 110 115 120 125 130 135 140 145 150 155 160 165 170 175 180 185 190 195 200 205 210 215 220 225 230 235 240 245 9999

the locking-ring 13 has been similarly placed, the latter being held in position by a sheet-metal ring 25. The rings 21 and 22 and the sheet-metal ring 25 are secured together by rivets 26. This structure, which may be readily secured in the door-casing and removed therefrom, constitutes the locking mechanism. The door-casing is provided with lugs 27 and 28, which coöperate with the lugs 23 and 24 on the ring-housing to hold the latter in place in the door-casing, these lugs being so proportioned and arranged that the locking mechanism may be inserted in the door-casing and then turned for bringing the retaining-lugs in proper engaging relations, as will be readily understood. The locking-rings 13 and 14 are capable of rotation in their respective seats, but should be fitted therein as snugly as is consistent with free rotation. At the rear of the door is a pin 29, which when the door is rotated travels in a path directly above the locking-ring 14 and engages with a pin 30, projecting from said ring, so that the latter may be moved or rotated by means of the door. Ring 13 is provided with a pin 31, which is engaged by a pin 32 on ring 14, so that said ring 13 may also be rotated in a similar manner. When the door is to be inserted in the casing, the locking-rings are placed in alinement with each other, as illustrated in Fig. 3. To facilitate this adjustment, there is a notch 33 in ring 14 and a similar notch 34 in ring 13. These notches must be in alinement with each other and opposite the index 6 on the door-casing. Now assuming the unlocking combination of the lock illustrated to be "32-89-0," the door will enter the casing when "0" on the dial is opposite the index on the door-casing. When the door is rotated, the lugs 7, 8, and 9 on its periphery will pass beneath the lugs 10, 11, and 12 in the casing, and continued rotation will cause the rings 13 and 14 to be moved from their adjusted positions and out of alinement with each other, thus preventing the door from being withdrawn or opened. It is here to be noted that the rings 13 and 14 are located slightly above the path of the coöperating locking-lugs 15, 16, and 17—i.e., said lugs are so located that they cannot come in contact with said rings unless the door be turned to the position which will place the lugs 7, 8, and 9 on its periphery opposite the spaces between the lugs 10, 11, and 12 in the door-casing. If the door be then pulled outwardly, the lugs 10, 11, and 12 will be against the locking-rings; but in this position the door will be held against rotation, because the lugs 7, 8, and 9 will be out of alinement with the space beneath the lugs 10, 11, and 12. This arrangement is of importance in that it prevents the positions of the locking-rings from being determined by means of the coöperating lugs. In unlocking the door it must first be rotated so that its pin 29 will be in engagement with pin 30 on ring 14 and

pin 32 on said ring in engagement with pin 31 on ring 13. If the rotation is then continued until the graduation-mark "32" is opposite the index 6, the ring 13 will be in its proper position of adjustment. Ring 14 is then adjusted by reversing the direction of rotation of the door, giving it one complete turn and continuing the movement until the next number in the combination "89" is opposite the index. It is then only necessary to reverse the direction of rotation until "0" is opposite the index to release the door from the lugs which hold it at its periphery. It is then free to be withdrawn from the casing.

15 In order to prevent a possible rotation of the ring-housing 18 when in place in the casing, I provide the under side of said housing with a spring-latch 35, which enters a notch 36 in a flange 37, surrounding the opening 20 into the safe or other receptacle. When the lock is inserted in the door-casing and turned for securing it therein, as already described, the latch 35 by entering the notch 36 serves to frictionally hold it in its proper position.

25 The latch 35 is preferably formed by stamping out a portion of the sheet-metal ring 25, as illustrated in Figs. 6 and 7. The ring-housing may, however, be secured in the door-casing by a set-screw, if desired.

30 The locking-rings 13 and 14 are exact counterparts except as regards the pins by which they are rotated. These pins are secured in holes, which are bored in the rings in the following manner: Beneath a suitable drill is placed a form, into which a ring may be inserted and rotated at will, so that a hole may be drilled at any point in the ring at a given distance from its center. No attention is paid to the radial location of the holes in any 35 of the rings. A single hole is drilled at random in ring 13, and the pin 31 is riveted therein. Six holes are drilled at random in ring 14, in one of which is riveted the pin 32. The other five holes are screw-threaded to receive the threaded shank of pin 30, which is shifted from one hole to another to change the combination of the lock. These holes are lettered "A," "B," "C," "D," and "E." When the rings are assembled in the ring-housing, the combinations required for opening the lock in all adjustments of pin 30 is determined in any suitable manner and stamped upon the rear of the housing, as shown in Fig. 6, "32-89" meaning that when 45 the pin 30 is inserted in hole "A" the opening combination is "32-89." "B-7-65" means that when pin 30 is inserted in hole "B" the opening combination will be "7-65," and so on. The complete opening combination 50 of the safe will include three numbers, the last number indicating the position to which the door must be turned after the tumblers have been adjusted. All of the numbers in the combination are, however, governed by 55 the location of pin 29 on the safe-door. The pin 30 may be changed from one hole to another without removing the lock from the

door-casing, but the recorded combinations being on the rear of the lock are hid from view and can only be read when the lock is 70 removed. By locating the pin-holes at random in the locking-rings the liability of producing two locks with the same opening combinations is reduced to a minimum, and as one lock may be readily substituted for another the changes in the combinations may be infinitely varied at pleasure.

Having thus described my invention, what I claim as new, and desire to secure by Letters Patent, is—

1. The combination with a circular door and its casing of lateral lugs or projections on said door, a plurality of circular tumblers adapted to coöperate with said lugs for locking the door to its casing, means whereby said tumblers may be adjusted by rotative movements of said door, and means for detachably securing said tumblers or rings in said casing and holding them together when removed therefrom, substantially as described. 90

2. The combination of a circular door provided with lateral lugs or projections, a door-casing, and a locking device consisting of a plurality of circular tumblers or rings rotatively mounted in and secured together by a cylindrical housing adapted to be inserted in and removed from said door-casing, said tumblers being adapted to engage with the lugs on said door, substantially as described.

3. The combination of a circular-door casing provided with one or more inwardly-projecting lugs, a circular door, having lateral lugs or projections, and a locking device consisting of a plurality of circular tumblers or rings rotatively mounted in a cylindrical housing, said rings being adapted to engage the lugs on said door, and the cylindrical housing being adapted to be engaged by the lugs in said door-casing, and means whereby said rings may be moved by rotative movements of said door, substantially as described. 105

4. The combination of a circular door provided with two or more peripheral lugs or projections, a circular-door casing provided with inwardly-projecting lugs corresponding in shape and relative location to the spaces between the lugs on said door and adapted to coöperate with said lugs for holding the door in said casing, a plurality of circular tumblers or rings detachably secured in said casing, 120 lugs or projections on said door adapted to coöperate with said rings for holding the door to its casing, and means whereby said rings may be rotated and separately adjusted by rotative movements of the door, substantially 125 as described.

5. The combination with a circular door provided with two or more peripheral lugs or projections, a circular-door casing provided with inwardly-projecting lugs corresponding in shape and relative location to the spaces between the lugs on said door and adapted to coöperate with said lugs for holding the door in said casing, one or more circular tumblers or

- locking-rings rotatively mounted in said casing, lateral projections on said door which move beneath portions of said ring or rings said lugs being so positioned as to be held 5 away from the rear surfaces of said rings by the lugs on the periphery of the door, and means whereby said rings may be rotated and separately adjusted by rotative movements of the door, substantially as described.
10. 6. The combination with a circular - door casing provided with inwardly - projecting lugs, of a locking device consisting of a plurality of circular tumblers or rings rotatively mounted in a cylindrical housing, said housing being provided with lateral lugs corresponding in relative location to the spaces between the lugs in said casing and adapted to engage therewith for holding the device in position therein, a circular door provided with 15 lugs or projections adapted to coöperate with said tumblers or rings for locking the door in the casing, and means whereby said tumblers or rings may be rotated and separately adjusted by rotative movements of said door, 20 substantially as described.
7. The combination with a circular - door casing provided with two or more inwardly-projecting lugs, of a locking device consisting of a plurality of tumblers or locking-rings 25 rotatively mounted in a cylindrical housing, said housing being provided with two or more peripheral projections corresponding in relative location to the spaces between the lugs in said casing and being adapted to engage 30 with said lugs for holding said device in the casing, a circular door provided with lateral projections adapted to coöperate with said tumblers or rings for locking said door, means whereby said rings may be rotated and separately 35 adjusted by rotative movements of the door, and means for holding the ring-housing against rotation, substantially as described.
40. 8. In a locking device for a rotatable circu-

lar door or cover, the combination of a plurality of circular tumblers or locking-rings, a 45 cylindrical housing for said rings, said housing being built up of counterpart rings each of which is countersunk around the central opening to form a seat for a locking-ring, and means for securing said housing-rings together, substantially as described.

9. In a locking device for a rotatable circular door or cover, the combination of a plurality of circular tumblers or locking-rings, a cylindrical housing for said rings, said housing being built up of counterpart rings, each of which is countersunk around its central opening to form a seat for a tumbler or locking-ring and provided with two or more peripheral projections, and means for securing 60 said housing-rings together, substantially as described.

10. In a locking device for a rotatable circular door or cover, the combination of a plurality of circular tumblers or locking-rings, a 65 cylindrical housing provided with interior annular grooves in which said tumblers are rotatively mounted, a pin on each of said tumblers projecting in the path of the pin on the next adjacent tumbler, a series of holes in 70 the uppermost tumbler each of which is appropriately marked with an identifying character, a pin adapted to be mounted in and shifted from one of said holes to another, and a series of characters on the device indicating the opening combinations of the lock 75 which will result from the shifting of said pin from one of said holes to another, substantially as described.

In testimony whereof I have hereunto set 80 my hand in presence of two subscribing witnesses.
